(57) **CLAIM**

The ornamental design for a tapered shoulder tenon cutter, as shown and described.

DESCRIPTION

FIG. 1 is a perspective view of a tapered shoulder tenon cutter, showing my new design.

FIG. 2 is a front elevation view (showing the shoulder-cutting blade) of the tapered shoulder tenon cutter of FIG. 1.

FIG. 3 is a right side elevation view of the tapered shoulder tenon cutter of FIG. 1.

FIG. 4 is a rear elevation view (showing the second blade) of the tapered shoulder tenon cutter of FIG. 1.

FIG. 5 is a top plan (or tool securing end) view of the tapered shoulder tenon cutter of FIG. 1; and,

FIG. 6 is a bottom plan (or working end) view of the tapered shoulder tenon cutter of FIG. 1.

Portions or features of the tapered shoulder tenon cutter not shown in the drawings form no part of the claimed design.
